UNITED STATES PATENT OFFICE.

WILLIAM R. SMITH, OF BUFFALO, NEW YORK, ASSIGNOR TO BUFFALO LEATHER CO., OF BUFFALO, NEW YORK, A CORPORATION OF WEST VIRGINIA.

APPARATUS FOR DYEING TEXTILE MATERIALS.

1,111,104.

Specification of Letters Patent.

Patented Sept. 22, 1914.

Application filed March 1, 1913. Serial No. 751,484.

To all whom it may concern:

Be it known that I, WILLIAM R. SMITH, a citizen of the United States, and a resident of Buffalo, in the county of Erie and 5 State of New York, have invented certain new and useful Improvements in Apparatus for Dyeing Textile Materials, of which the following is a specification.

This invention relates to apparatus for 10 dyeing textile materials either in the form of thread and yarn or woven fabrics, the material to be dyed being immersed in a body or bath of liquid dye contained in a tank or reservoir, and agitated by air forced 15 into the bottom of the tank, the dye liquor being at the same time heated and preferably moved progressively, so that the material is caused to pass over the air inlets provided in the bottom of the tank and is 20 thereby thoroughly impregnated with the dye liquor; the air ascending through the heated dye liquor not only agitating the liquor but bringing about a chemical reaction in such manner that a fast color is 25 imparted to the material.

The invention has for its object to enable 30 an apparatus of the general character indicated to be operated with the greatest possible economy of heat and dye liquor, and ac- 35 cording to this invention the apparatus is so devised that the dye liquor is heated while air is passing through it and that the heated air and vapor rising from the dye liquor are returned to the bottom of the tank, so that practically no heat is lost, and the dye material which rises with the vapor is returned to the bath.

In order that the said invention may be 40 clearly understood and readily carried into effect the same will now be described more fully with reference to the accompanying drawings, in which:—

Figure 1 represents a plan view, Fig. 2 represents a side elevation. Fig. 3 represents an end elevation of a dyeing apparatus embodying my invention. Fig. 4 represents a perspective view of part of the apparatus. Fig. 5 is a plan view of one of the twyers which may be used with the apparatus as hereinafter explained. Fig. 6 represents a section on line 6—6 of Fig. 4. Fig. 7 represents a section on line 7—7 of Fig. 5. Fig. 8 is a detail plan view showing the pipe connections with the twyers 50 more clearly shown than in the preceding

figures. The same reference characters refer to the same parts in all the figures.

a represents a tank or reservoir which is preferably of elliptical trough formation although it may be of any other suitable 60 form. The tank as here shown is of the general form represented by the drawings of the prior United States Patent No. 864,343 dated August 27, 1907, and is provided with paddle wheels *b* revolved by 65 shafts *c* journaled in bearings above the tank, the wheels being rotated simultaneously in opposite directions by mechanism which may be similar to that shown by the drawings forming part of the aforesaid prior patent, so that a body of dye liquor in said tank is caused to circulate 70 therein. I have not represented the mechanism for rotating the paddle wheels, the same forming no part of the present invention. The tank is provided with a closely fitting top *d* and with paddle boxes *e* located over the paddle wheels, said top and boxes forming a practically air tight cover which 75 closes the tank and prevents loss of dye liquor by evaporation therefrom. The end portions *d'* of the cover are hinged and adapted to be raised to afford access to the tank.

In the bottom of the tank are twyers *f* 80 having narrow elongated air outlets *g* adapted to discharge air upwardly into the body of dye liquor. These twyers are connected by conduits or outlet pipes *i*, *j*, with the outlet *k'* of an air pump *k* which forces 85 air simultaneously through all the twyers. The inlet *k* of the air pump is connected by conduits or suction pipes *m* with an opening in the cover of the tank, and preferably situated in that part of the cover 90 formed by the paddle boxes *e*. The air pump therefore draws air from the top of the tank and returns the said air through the twyers *f* to the bottom of the tank so that a continuous circulation of the said air 95 is maintained.

In this embodiment of my invention I employ the means next described for heating the dye liquor:—Each of the twyers *f* is sub-divided by a partition *f'* (Figs. 5, 6 and 105 7) into two chambers, one of which communicates with the air outlet *g* and conduit *i*. The other of said chambers communicates with a steam conduit *o* and is provided with a narrow elongated steam outlet *p* located 110

beside the air outlet g and adapted to discharge steam upwardly into the body of dye liquor. The steam conduits o entering the several twyers are branches of a steam conduit which, as here shown, includes a dye receptacle or drum r communicating with steam conduits or pipes q , q' , the pipe q admitting steam from the source of supply to the drum while the pipe q' conducts steam 10 from the drum to the branch pipes o entering the twyers as is best seen in Fig. 8. The drum r and the steam pipes q' and o are utilized not only for conducting steam to the twyers but also for introducing fresh dye 15 liquor or material into the tank in a thoroughly mixed condition. To this end the drum is provided with a dye inlet or funnel t for the reception of the dye liquor, said funnel having a neck t' provided with a 20 valve u . The pipes q and q' are provided respectively with valves v and v' . When the valve u is closed, and the valves v v' are opened, the drum r is simply a part of the steam conduit which supplies steam to the 25 twyer outlets p , this being the normal condition during the dyeing operation. When more dye liquor is to be introduced, the valves v and v' are closed and the valve u is opened. The drum r is then charged with 30 dye liquor after which the valve u is closed and the valves v v' are opened. The steam pressure now forces the dye liquor from the drum through the steam outlets p into the tank so that the dye liquor in the tank may 35 be strengthened at any time by fresh dye materials without opening the top of the tank, the dye material being uniformly distributed by the steam.

The steam supply should be sufficient to 40 maintain the dye liquor in the tank at a temperature of substantially 212° F. The vapor given off by the dye liquor at this temperature carries with it more or less of the dye material which would be wasted if 45 the vapor were allowed to escape. The mixture of steam or vapor, air and particles of dye liquor collected at the top of the tank is returned to the tank by the pump k so that there is no considerable loss either of dye or 50 heat.

The air co-operates with the heated dye liquor in quickly imparting a fast color to the material inserted therein.

I do not limit myself to an apparatus embodying an endless tank and means such as the paddle wheels b for circulating the dye liquor.

The tank may be of any other desired form and other means may be employed for 55 circulating the liquor or the circulating 60 means may be omitted.

It will be observed that the heating steam is discharged into the bath of dye liquor contained in the tank, simultaneously with the agitating air, so that the steam performs the double function of heating and 65 agitating the bath.

What I claim and desire to secure by Letters Patent is:—

1. A dyeing apparatus comprising a 70 closed tank adapted to contain a bath of dye liquor, means for admitting steam to the lower portion of the tank below the level of the dye liquor, and an air pump outside the tank having a suction pipe communicating 75 with the top of the tank and another pipe discharging into the lower portion of the tank below the level of the dye liquor, said air pump forcing agitating air into the dye liquor and returning thereto the mixture of 80 air, steam and particles of dye liquor collected at the top of the tank.

2. A dyeing apparatus comprising a 85 closed tank adapted to contain a bath of dye liquor, an air pump having its inlet connected with the top of the tank and its outlet connected with the bottom of the tank and adapted to discharge air into the bath, means adapted to conduct steam into the bottom of the tank and discharge the same 90 into the bath, and means for introducing fresh dye material into the steam conducting means whereby the fresh material is uniformly distributed through the bath by the steam.

3. A dyeing apparatus comprising a 95 closed tank, a twyer having a plurality of outlets communicating with the bottom of the tank, an air pump having its inlet connected with the top of the tank and its outlet connected with one of the twyer outlets, and a steam conduit connected with another twyer outlet.

4. A dyeing apparatus comprising a 100 closed tank, a twyer having a plurality of outlets communicating with the bottom of the tank, an air pump having its inlet connected with the top of the tank and its outlet connected with one of the twyer outlets, a steam conduit connected with another 105 twyer outlet, said conduit being provided with a dye receptacle having a valved dye inlet, and with valves whereby the conduit may be closed to permit the insertion of dye material in said receptacle.

In testimony whereof I have affixed my 110 signature, in presence of two witnesses.

WILLIAM R. SMITH.
